DESIGN FOR A TEXTILE FABRIC

Sidney S. Gutlon, Newton, Mass., assignor to
Modern Curtain Co. Inc., Boston, Mass., a cor-
poration of Massachusetts

Application August 16, 1935, Serial No. 58,155

Term of patent 14 years

To all whom it may concern:

Be it known that I, Sidney S. Gutlon, a citizen of the United States, residing at Newton, in the county of Middlesex and State of Massachusetts, have invented a new, original, and ornamental Design for a Textile Fabric, of which the following is a specification, reference being had to the accompanying drawing, forming part thereof.

The figure of the drawing is a plan view of a portion of the fabric showing my design and the characteristic feature of said design resides in adjacent parallel areas in a woven fabric having

groups or sheds of threads of progressively increasing number and progressively increasing density from one side edge of each area to the other side edge thereof, producing successive parallel stripes each of graduated woven shadow effect from one side edge to the other side edge thereof.

I claim:

The ornamental design for a textile fabric substantially as shown and described.

SIDNEY S. GUTLON.
